ELECTROLYTIC CELLS

William C. Gardiner, Niagara Falls, N. Y., assignor to The Mathieson Alkali Works, Inc., New York, N. Y., a corporation of Virginia

Application March 14, 1942, Serial No. 434,751

2 Claims. (Cl. 204—231)

1

My invention relates to improvements in cells for the production of magnesium by electrolysis of magnesium chloride fusions to which magnesium chloride is supplied as a hydrous salt. Various forms of cells have been proposed for carrying out this electrolysis. In one such general form, the cell is divided to provide an electrolysis compartment and a feed compartment, anode and cathode elements are arranged in the electrolysis compartment, provision is made for circulating electrolyte from the feed compartment through the electrolysis compartment and back to the feed compartment and the hydrous magnesium chloride supplied to the electrolysis is introduced into the feed compartment where dehydration is effected and the resulting anhydrous magnesium chloride is incorporated in the electrolyte. Such dehydration tends to involve decomposition of the salt with formation of magnesium oxide and liberation of hydrochloric acid which, to the extent that it occurs, imposes operating burdens on the cell and involves a corresponding loss in efficiency. Such decomposition can be suppressed by maintaining free chlorine present in the region of dehydration and incorporation of the magnesium chloride into the electrolyte. Considerable heat is liberated by passage of the electrolyzing current through the electrolyte. Within limits this heat can be relied upon to maintain the magnesium chloride fusion constituting the electrolyte at proper operating temperature. These limits vary with different cells depending more particularly upon the characteristics with respect to thermal losses. However, if this source of heat is relied upon to maintain the fused electrolyte at operating temperature, control of the electrolysis is made dependent upon the thermal losses of the cell. Optimum conditions of production and efficiency are seldom if ever met under these conditions because of the diverse requirements of the cell, thermally and electrically. The heat liberated by the electrolysis can be supplemented externally or internally, for example by arranging the cell in a heating furnace or by making the electrolyte a resistor in an electrical circuit to which electrical energy for thus heating the electrolyte is supplied. The improvements of my invention, embodied in this general form of cell, provide for independent control of the cell thermally, as well as electrically, and for suppression of the decomposition to which I have referred in a simple and advantageous manner.

The improved cell of my invention comprises an electrolysis compartment and a feed compartment from which fused electrolyte circulates to

2

and through the electrolysis compartment and back to the feed compartment and to which the hydrous salt is supplied, and an anode and cathode in the electrolysis compartment. In the improved cell of my invention, one or more electrodes is arranged in the feed compartment, to be immersed in the electrolyte during operation, means are provided for passing an alternating current through these electrodes and the electrolyte in the feed compartment in which the electrodes are immersed, and an electrical connection is established between these electrodes and the anode in the electrolysis compartment rendering the electrodes anodic with respect to the electrolyte. Control of the rate at which energy is thus supplied as alternating current, a control which does not affect the electrolysis, affords independent thermal control of the cell. And, these electrodes being anodic with respect to the electrolyte, chlorine is liberated at these electrodes which acts to suppress unwanted decomposition in the feed compartment. Dehydration of the hydrous magnesium chloride supplied to the feed compartment, and the fusion of the salt thus supplied, constitute one of the larger thermal burdens on the cell. Thus, in the improved cell of my invention, the supplementary heat is supplied in a particularly advantageous region and, coupled with this supply of heat, chlorine acting to suppress decomposition is introduced into the region in which there is the greatest tendency toward decomposition. The magnesium liberated by the current flow producing chlorine at the electrodes in the feed compartment is liberated as part, a relatively small part, of the cell's production of magnesium. This unusual combination of functions simplifies the cell, and its operation, while accomplishing independent thermal control of the cell and suppression of decomposition with the advantages I have indicated.

The accompanying drawing illustrates one form of cell embodying my invention. This cell is illustrated diagrammatically and conventionally, in sectional elevation with parts broken away in Fig. 1, and Figs. 2 to 5 inclusive illustrate four arrangements of the electrical circuits used in conjunction with the cell proper illustrated in Fig. 1.

The cell illustrated comprises a steel shell 6 lined with refractory 7, a refractory partition 8 divides the cell into an electrolysis compartment 9 and a feed compartment 10. A steel cathode plate 11 is supported above the electrolysis compartment by ledges on the refractory lining of the

shell 6. An electrical connection 12 to this plate 11 extends through the top of the cell. A cylindrical steel cathode element 13 is suspended from and electrically connected to the plate 11, for example by welding. A port 14 is provided to permit the escape beneath the plate 11 from within the element 13 of magnesium liberated by the electrolysis. A cylindrical steel baffle 15 and a cylindrical refractory liner 16 serve to trap such magnesium beneath the plate 11 whence it flows into the metal collecting well 17 where it collects on the surface of the magnesium chloride fusion as indicated at 18. A removable cover 19 is provided to permit removal of the recovered magnesium from the cell. A graphite anode 20 extends into the electrolysis compartment through an anode compartment 21 and the cylindrical refractory baffle 16. The anode compartment is formed of a refractory floor 22, the upper part of the refractory partition 8, the refractory partition 23 in the form of an incomplete cylinder and a cover 24. A passage 25, below the normal electrolyte level, connects the anode compartment with the feed compartment. The anode compartment is also connected with the electrolysis compartment through the space within the baffle 16 around the anode 20. Chlorine separating in the anode compartment is collected for recovery through connection 26. Additions to maintain the composition and quantity of the electrolyte, including hydrous magnesium chloride, are supplied to the feed compartment 19 through connection 21. Water vapor and hydrochloric acid gas and any unreacted chlorine liberated in the feed compartment escape through connection 28. Connections 27 and 28 open through a cover 29. A pair of graphite electrodes 30 and 31 extend through cover 29 into the feed compartment to a level below the normal electrolyte level.

The anode 20 and the cathode 13 are connected to a source of direct current of appropriate voltage, 6.5-8.5 volts for example, in the conventional manner as indicated in each of Figs. 2, 3, 4 and 5. The electrodes 30 and 31 are connected to a source of alternating current, 60 cycle current for example, as illustrated in these figures. Referring first to Figs. 2 and 3, the electrodes 30 and 31 are connected across the secondary of a transformer 32. An individual transformer is with advantage used with each electrolytic cell. The transformer must be insulated to withstand the direct current potential above ground of the cell as well as the alternating current potential and the secondary winding must be designed to carry the direct current as well as the alternating current. The electrodes 30 and 31 are made anodic by an electrical connection between these electrodes and the anode 20. As illustrated in Fig. 2, this connection there designated 33 may be a connection between the anode 20 and the electrode 30 directly and the electrode 31 through the transformer secondary. As illustrated in Fig. 3 this connection there designated 34 may be made to a midpoint of the transformer secondary. Now referring to Figs. 4 and 5, the transformer secondary may be connected across the anode 20 and a single electrode in the feed compartment, as illustrated in Fig. 5, or across two or more electrodes connected in parallel in the feed compartment as illustrated in Fig. 4. The supplementary heating of the electrolyte effected by passage of the alternating current through the electrolyte as a resistor can be controlled, for example, by regulating the immersion of the electrodes 30 and 31 or by regulating the voltage at 75

which alternating current is supplied to these electrodes. The rate of chlorine liberation in the feed compartment at the electrodes 30 and 31 can be controlled by regulating the immersion of these electrodes, and this rate of chlorine liberation and the supplementary heating can be independently controlled by first establishing the appropriate rate of chlorine liberation by regulating the immersion of the electrodes and then establishing the rate of heat supply in the feed compartment by regulating the voltage of the alternating current supply.

In operation, the cell is charged with fused electrolyte to approximately the level indicated in Fig. 1. This electrolyte, previously designated a magnesium chloride fusion, may consist for example of a fused mixture of chlorides, including magnesium chloride and one or more of the chlorides of sodium, potassium and calcium. Other salts such as sodium fluoride may also be included. The proportion of magnesium chloride may range from 5% to 50% by weight on the total for example. This electrolyte is maintained at a temperature of 700°-800° C. for example. Magnesium liberated at the cathode collects beneath the cathode plate and flows into the metal collecting well 17. Chlorine liberated at the anode 20 rises through the baffle 16 into the anode compartment 21. The electrolyte circulates upwardly through the electrolysis compartment 9 to the anode compartment 21, through the passage 25 from the anode compartment to the feed compartment 19 and from the feed compartment 10 beneath the partition 8 into the electrolysis compartment 9. As the electrolysis proceeds, hydrous magnesium chloride containing from 1 to 2 moles of water per mole of magnesium chloride for example is introduced into the feed compartment, where chlorine is also liberated at electrodes 30 and 31. The hydrous magnesium chloride is with advantage introduced in the form of pellets having a density approximating that of the electrolyte and containing, for example, about 1% of free carbon. The hydrous salt is dehydrated in the feed compartment and fused, and its anhydrous component is incorporated into the electrolyte to maintain the concentration of magnesium chloride. Thermal requirements of the cell, in excess of the heat liberated in connection with the electrolysis, including the heat required for dehydrating and fusing the hydrous magnesium chloride feed, are supplied to the electrolyte in the feed compartment independently of the electrolysis as previously described.

55 I claim:

1. In cells for the production of magnesium by electrolysis of a magnesium chloride fusion to which magnesium chloride is supplied as a hydrous salt, comprising an electrolysis compartment and a feed compartment from which fused electrolyte circulates to and through the electrolysis compartment and back to the feed compartment and to which the hydrous salt is supplied and an anode and a cathode in the electrolysis compartment, the improvement which comprises an electrode in the feed compartment, and means for passing an alternating current through said electrode and the electrolyte in the feed compartment in which it is immersed, said means comprising an electrical connection between said electrode and said anode rendering the electrode anodic with respect to the electrolyte.

2. In cells for the production of magnesium by electrolysis of a magnesium chloride fusion to which magnesium chloride is supplied as a hy-

drous salt, comprising an electrolysis compartment and a feed compartment from which fused electrolyte circulates to and through the electrolysis compartment and back to the feed compartment and to which the hydrous salt is supplied and an anode and a cathode in the electrolysis compartment, the improvement which comprises a pair of electrodes in the feed compartment, means for passing an alternating current through the electrolyte in the feed compartment between said electrodes, and an electrical connection between said electrodes and said anode rendering the electrodes anodic with respect to the electrolyte.
